UNITED STATES PATENT OFFICE.

JOHN CONNOLLY, OF DETROIT, MICHIGAN.

DESIGN FOR A RUBBER VEHICLE-TIRE.

44,298.

Specification for Design.

Patented July 8, 1913.

Application filed March 5, 1913. Serial No. 752,226. Term of patent 14 years.

To all whom it may concern:

Be it known that I, JOHN CONNOLLY, a citizen of the United States, residing at Detroit, in the county of Wayne, State of Michigan, have invented a new, original, and ornamental Design for a Rubber Vehicle-Tire, of which the following is a specification, reference being had to the accompanying drawing, forming part hereof.

The figure of the drawing is a perspective view of a section or portion of a tire showing my new design.

I claim:

The ornamental design for a rubber vehicle tire, as shown.

Signed at the city of Detroit, county of Wayne and State of Michigan, this 15 day of February, 1913.

JOHN CONNOLLY.
